HEAT TRANSFER ELEMENT SUPPORTED
AGAINST EXTERNAL OR INTERNAL
PRESSURES

Eugene W. Wasielewski, South Euclid, Ohio

Application February 16, 1950, Serial No. 144,551

5 Claims. (Cl. 257—235)

(Granted under Title 35, U. S. Code (1952),
sec. 266)

1

This invention relates to heat exchangers of the type that may be subjected to high pressure differentials in practice, such as for example in some exhaust coolers for internal combustion power plants.

The object of the present invention is to devise a novel construction of effective yet simple and light weight heat exchangers adaptable for use with any fluids in extremely high pressure and temperature ranges.

More specifically, the object is to construct a heat exchanger unit including a tube system, wherein the tubes are also used for bracing the walls of the unit against high pressure differentials, thereby permitting the use of very thin walls for reducing the overall weight of the unit as well as improving heat transfer characteristics.

Other and more specific objects will appear in the following detailed description of one form of the device constructed in accordance with the teachings of the present invention, having reference to the accompanying drawings, wherein:

Fig. 1 is a perspective view of the heat exchanger unit partly broken away to show some details of the construction.

Fig. 2 is a side view partly broken away to show the arrangement of tubes and baffles.

Fig. 3 is a plan view of the device also broken away for a similar purpose.

Fig. 4 is a sectional view taken on the line 4—4 of Fig. 2.

Fig. 5 is another sectional view, taken on the line 5—5 of Fig. 2.

Figs. 6, 7 and 8 are detail sectional views taken on the lines 6—6, 7—7 and 8—8 respectively of Fig. 5, and

Fig. 9 is an enlarged detail sectional view taken on the line 9—9 of Fig. 3.

The present form of the device contemplates the assembly of any number of sections 1, 2 and 3 which may be made to one or more standard constructions adaptable for connection in series as shown, using a standard form of construction for each end section 4 and 5, adaptable for connection to the ends of the sections 1 and 3 respectively, to form the heat exchanger assembly.

The present device is a water-tube type heat exchanger with straight tubes which operate at pressures below atmosphere and are, therefore, subject to external pressures. The water-tube type exchanger is especially suitable for cooling gases at high temperatures above 2000° F.

Normally, when using known cooler construction, the external side walls thereof must ordinarily be heavily braced against the external or

internal pressures that may be encountered. Consequently, the normal cost of the heat exchangers is usually high and their heat transfer characteristics are limited by the heavy wall structure that is usually necessary to suitably reduce the required bracing.

In the present construction as illustrated, the heat exchanger tubes 6 and 7 are used conveniently in alternate rows running at 90° to each other, for bracing the walls 8 and 9 respectively, by fixing their ends to those walls by any suitable means such as welding at 10 and 11 as shown, or by rolling, threaded connections, etc. This construction permits the use of thin walls and therefore better heat transfer characteristics without sacrificing strength requirements; and the load is thus taken entirely by the cold external walls 12 and 13, through the baffles 14 and 15 which extend between the inner and outer walls 8 and 9, and 12 and 13 respectively.

In order to protect the inner walls 8 and 9 still further, water-tube walls 16 (Fig. 9) may be provided and laid in such manner as to prevent the extremely hot gases that may constitute the main flow through the exchanger from reaching these walls 8 and 9. The headers 17 and 18 for such a water wall are placed at the low temperature end 5 of the heat exchanger with U connections 19 at the high-temperature end 4. Further protection can be obtained by covering the walls 8 and 9 with a refractory material 20 (Fig. 9). By using all of these means, heat exchangers can be constructed for gases at very high temperatures, exceeding 4000° F. and pressures lower than $\frac{1}{2}$ " Hg absolute.

A flow of fluid may be established as shown through the rows of tubes 6 and 7 and around the baffles 14 and 15 or in any other way desired. The principal features of novelty being in using the heat exchanger tubes 6 and 7 arranged at right angles not only for conducting the fluid therein but also to serve as braces for the opposite walls obviating the use of heavy walls and special bracing structure for high temperature and pressure differential conditions. Another feature is the use of the water wall for protection against high temperatures as well as further reinforcement of the wall structure so it may be made of very thin material, the headers for the tubes of this water wall being placed in the low-temperature end of the heat exchanger, and the possible use of refractory material, if desired, between the water wall and the inner walls 8 and 9.

Coolant, for example water, patterns established in use of the heat exchanger shown are as

3

follows: The water wall 16 obtains its supply through an inlet line 30 (Fig. 6) which is connected to manifold 18. After circulating through the tubes of the water wall 16, or in the illustrated case, the tubes of the three individual but connected water walls, the water enters manifold 17 nested with manifold 18 (Fig. 7), and discharges through outlet line 32.

Separate from the above described is the flow in the water jackets (Figs. 2 and 3). Here, water enters inlet 34 and flows to distributor 36 (Fig. 5), whence the water is delivered to the jackets of section 3 through suitable pipes. After passing through the jackets in the flow pattern shown by the direction arrows of Figs. 2 and 3, the jacket water enters the jackets of section 2 and finally 1 through suitable couplings 38 that connect with piping similar to that described for the inlet of water to section 3. After the water has progressed through section 1, it enters discharge pipe 40 serving as an outlet, after passing through pipes and distributor 42, similar to distributor 36.

Many obvious modifications in the details and arrangement of parts may be made without departing from the spirit and scope of the invention as defined in the appended claims.

The invention described herein may be manufactured and used by or for the Government of the United States of America for governmental purposes without the payment of any royalties thereon or therefor.

What is claimed is:

1. In a heat exchanger, a plurality of heat exchange sections coupled together, each heat exchanger section comprising an inner wall arranged to define a central passage to conduct a hot fluid, the passage having open ends for through passage of hot fluid, a first row of coolant carrying heat transfer conduits, each conduit being fastened at both of its ends to opposed portions of said wall, a second row of coolant carrying heat transfer conduits, each of which is fastened to other opposed portions of said wall, said rows of conduits being arranged at substantially right angles to each other to thereby brace said wall against the forces of internal and external pressures, an outer wall surrounding said inner wall, means fixing said walls in spaced relationship to each other to define a jacket, said inner wall being provided with a plurality of apertures which are arranged to communicate the bores of said conduits with said jacket, an inlet line connected to said jacket, an outlet line connected with said jacket and having a coupling thereon to connect with the inlet line of an adjacent section, a plurality of tubes arranged to constitute a water wall, said tubes being located interiorly of and parallel to said inner wall, and inlet and outlet means connected with and for said plurality of tubes.

4

2. The construction of claim 1 wherein said outlet means comprises a header located within said passage, and an outlet line connected to said header.

3. The construction of claim 2 wherein said inlet means comprises a second header connected to said tubes and provided with an inlet line, and said headers being nested with each other so as to transfer heat between each other, one of said headers extending entirely around the inner surface of a cross sectional part of said passage.

4. In a heat exchanger, a heat exchanger section comprising an inner wall arranged to define a central passage to conduct a hot fluid and having an inlet and an outlet end, a first row of coolant carrying heat transfer conduits, each conduit being fastened at both of its ends to opposed portions of said wall, a second row of coolant carrying heat transfer conduits, each of which is fastened to other opposed portions of said wall, said rows of conduits being arranged at substantially right angles to each other to thereby brace said wall against the forces of internal and external pressures, an outer wall surrounding said inner wall, means fixing said walls in spaced relationship to each other to define a jacket, said inner wall being provided with a plurality of apertures which are arranged to communicate the bores of said conduits with said jacket, an inlet line connected to said jacket, an outlet line connected with said jacket, a plurality of tubes, each tube being U shaped and arranged within said inner wall adjacent to the inner surface thereof, said tubes constituting a water wall and having their ends located at the low temperature outlet end of said passage, means constituting an outlet for said tubes connected with one end of each tube, and means constituting an inlet for said tubes comprising a header located in said passage and connected to the other end of each tube.

5. The construction of claim 4 and a lining of refractory material disposed between said tubes and the inner surface of said inner wall and at least partially held in place by said tubes.

EUGENE W. WASIELEWSKI.
